UNITED STATES PATENT OFFICE.

WILLIAM R. STIRLING, OF CHICAGO, ILLINOIS, ASSIGNOR TO HIMSELF, AND
ALEXANDER J. LEITH, OF NEW YORK, N. Y.

METALLIC DOOR.

SPECIFICATION forming part of Letters Patent No. 433,376, dated July 29, 1890.

Application filed July 12, 1889. Serial No. 317,284. (No model.)

To all whom it may concern:

Be it known that I, WILLIAM R. STIRLING, of Chicago, Cook county, Illinois, have invented a new and useful Improvement in Metallic Doors, of which the following is a full, true, and exact description, reference being had to the accompanying drawings.

This invention relates to an improved sliding door, and is especially adapted to that class of doors used to close freight-cars, but may be used for other purposes; and it consists of a combination of such door with supporting and closing devices, whereby the same is readily opened and closed, and when closed is tight against the ingress of moisture.

My door itself consists of a box-shaped structure of pressed steel having inwardly-projecting flanges at the sides, and preferably at the top, formed integral with the door itself, while the body of the door is preferably made of corrugated material.

The method of sustaining this door will be readily understood from the accompanying drawings, in which—

25 Figure 1 represents an elevation, and Fig. 2 a horizontal cross-section.

A represents the door, preferably box-shaped in structure, and preferably corrugated, as indicated. The said door has inwardly-projecting flanges F G at the sides, which flanges are by preference carried around the top and bottom, as indicated at L. The door itself is carried upon the rail H by means of rollers J J. At one side of the opening of the door is the flange E, against which the flange F engages when the door is closed. At the opposite side is the flange or projection D, against which the flange G engages

when the door is closed, and the flange F may engage when the door is open. The flange D must not project beyond the inner surface of the corrugations. These flanges or strips D E may be supported in any suitable way—as, for instance, upon the posts B C. When the door is closed, both flanges D E engage 45 with the flanges F G of the door, while when the door is open the flange D arrests the further motion of the part F of the door.

What I claim as my invention, and desire to secure by Letters Patent, is—

1. The pressed-steel door having corrugations in the body thereof, and inwardly-projecting flanges on two sides, all made of one piece of metal, substantially as described.

2. The corrugated door A, having a flange 55 extending around the same and made of pressed steel and of one piece of metal, substantially as described.

3. The combination of the corrugated door A, the internally-projecting flanges F G, integral with the door, and the stationary strip D, engaging with the flanges F G, substantially as described.

4. The combination of the corrugated door A, the internally-projecting flanges F G, integral with the door, and the stationary strips D E, engaging with the flanges F G, substantially as described.

In testimony whereof I have signed my name to this specification in the presence of two 70 subscribing witnesses.

WILLIAM R. STIRLING.
